INVENTOR,

BY James W. Wilt
Lillian J. Barth Jr.

ATTORNEY.

UNITED STATES PATENT OFFICE

2,559,744

PAPER HOLDER FOR DRAFTSMEN

James W. Wilt, Taft, Calif.

Application September 16, 1946, Serial No. 697,260

3 Claims. (Cl. 24—67)

1

The present invention relates to an adhesive tool or appliance for holding a sheet of paper on a drawing board or other flat surface.

The principal object of the invention is to provide a convenient appliance, for use primarily by draftsmen, for the purpose of temporarily attaching the edges of a sheet of drawing or tracing paper to the surface of a drawing board or table, or to an underlying sheet of drawing or map.

Another object is to provide an attaching appliance or holder which will not mar the surfaces to which it is applied. In many cases, particularly in tracing, the use of thumb tacks is undesirable or impossible, such for example as when working on a transparent tracing table, or on a glass or highly finished desk top without a drawing board, or when tracing from a wall map, or when making a tracing of a portion of a large drawing or map. In such cases, the draftsman customarily uses paper weights, which may allow the tracing to slip, or patches of adhesive tape, which are hard to remove.

Further objects of the invention are to provide a holder which is easy to remove from the drawing paper and board, which can be used repeatedly until its adhesive element is worn out, and in which the adhesive element can be quickly and easily replaced.

Other objects and advantages of the invention will become apparent from the following description which should be read with the understanding that changes, within the scope of the claims hereto appended, may be made in the form, construction and arrangement of the several parts without departing from the spirit of the invention as defined in said claims.

Reference will be made to the accompanying drawings in which

Fig. 1 is a perspective view of a preferred embodiment of the invention showing the three elements thereof disassembled.

Fig. 2 is a vertical section of the same showing the elements assembled.

Fig. 3 is a perspective view of a modified form of the invention with the adhesive element omitted.

Fig. 4 is a vertical section of the parts shown in Fig. 3 with the adhesive element in place.

In the drawings, and referring for the moment to Figs. 1 and 2 thereof, the reference numeral 5 designates a rectangular and preferably square block of resilient or elastic material such as rubber, having a flat bottom surface 6 and substantially vertical and parallel sides 7, which constitutes the central portion of the holder. The

2

corners where the sides meet the bottom are preferably rounded, as shown at 8. A lateral flange 9 near the top of the block or central portion projects outwardly beyond the planes of the sides 7.

5 A rectangular frame 10 of inelastic material, whose four sides constitute side portions of the holder, has interior dimensions very slightly larger than the exterior dimensions of the lower portion of the block 5, so that it fits over the sides 7 and abuts against the bottom of the projecting flange 9. The height of the frame 10 is materially less than the vertical distance between the bottom of the block and the bottom of the flange 9, so that no portion of the frame 10 can touch the surface on which the block rests.

10 A sheet or strip 11 of thin flexible material, coated with non-drying adhesive on its lower surface, is placed beneath the bottom of the block or central portion 5, and its ends 12 are brought up against the sides 7 of the block and turned outwardly at the flange 9. The frame 10 is then brought upwardly around the lower portion of the block and the sheet 11 which lies beneath and against the sides thereof, thereby clamping the adhesive sheet around and against the bottom of the block, as shown in Fig. 2. The width of the adhesive sheet 11 is the same as the width of the lower portion of the block.

15 When assembled, as shown in Fig. 2, my holder constitutes a block-like appliance having a flat adhesive bottom. In using it, it is pressed down firmly on the drawing board or table or on the underlying drawing or map as the case may be, with a portion of its bottom overlapping the edge of the superposed tracing paper. The flat adhesive bottom of the device adheres to both the paper and the exposed surface of the underlying board or drawing, and thereby securely holds the paper in place.

20 30 35 The holder may be removed from the surfaces to which it adheres simply by lifting it up carefully. The fit of the frame 10 about the lower portion of the block 5 is sufficiently close so that the adhesive element 11 is securely clamped therebetween and remains so clamped when the entire holder is pulled away from the underlying surface to which it adhered.

40 45 The holder may be removed from and re-applied to the surface of the drawing board repeatedly, as long as the adhesive element 11 retains sufficient adhesive quality. When the adhesive element is worn out, it can be readily replaced with a fresh one by removing and replacing the frame 10.

50 55 A modified form of my adhesive holder, shown

in Figs. 3 and 4, comprises a block having a central portion 13 of resilient or elastic material provided with a flat lower surface 14 and substantially vertical parallel sides 15. A pair of arms or wings 16, constituting side portions of the holder, are formed integrally with the central portion 13 at one end and are spaced from the sides 15 by narrow slots 17. The adhesive element 11 is the same as in the previously described form of the invention and consists of a strip or sheet of thin flexible tape having adhesive applied to its lower surface. The adhesive element is fitted under the bottom of the block 13, and its ends are brought up through the slots 17, as shown in Fig. 4.

The adhesive outer surfaces of the upstanding end portions of the strip 11 are caused to adhere to the inside surfaces of the wings 16 by squeezing said wings against the sides of the central portion of the block, thereby holding the adhesive element in place against the bottom and sides of the central portion of the block. This form of holder is used in the same manner as the previously described form. The adhesive element can be replaced by spreading the wings 16 apart to widen the slots 17 and release the ends of said adhesive element.

I claim:

1. Means for temporarily attaching a sheet of paper to a flat surface comprising a holder formed of resilient elastic material and having a block-like central portion with a flat horizontal bottom and the sides rising therefrom, said holder having wings integral at one end therewith and positioned adjacent to two opposite sides thereof, and a piece of flexible tape having a non-drying adhesive lower surface lying beneath the flat bottom of said central portion and having its ends bent upwardly between said sides and said wings.

2. Means for temporarily attaching a sheet of paper to a flat surface comprising a holder having a block-like elastic central portion and side portions, said central portion having a flat horizontal bottom and sides rising vertically therefrom to form a block of sufficient vertical thick-

ness whereby it may be lifted from a horizontal surface by grasping its vertical sides, said side portions lying adjacent to two opposite sides of said central portion, the bottoms of said side portions being above the plane of the bottom of said central portion, and a flexible sheet positioned beneath and in contact with the bottom of said central portion, said sheet having its lower surface coated with non-drying adhesive, and said sheet having its ends turned upwardly and removably positioned between said side portions and the sides of said central portion.

3. Means for temporarily attaching a sheet of paper to a flat surface comprising an elastic holder having a flat horizontal bottom and sides rising therefrom to form a block of sufficient thickness whereby it may be lifted from a horizontal surface by grasping its sides, flanges projecting outwardly from at least two opposite sides of said block near the top thereof, a removable frame having at least two spaced side portions fitted closely against the flanged sides of said block below said flanges, the bottom of said frame being above the bottom of said block, and a flexible sheet positioned beneath and in contact with the bottom of said block, said sheet having its lower surface coated with non-drying adhesive, and said sheet having its ends turned upwardly and removably clamped between the side portions of said frame and the sides of said block.
